CLAIM

We claim the ornamental design for drop filter top cap, as shown.

DESCRIPTION

FIG. 1 is a perspective view of the drop filter top cap according to an embodiment of the present invention;

FIG. 2 is another perspective view of the drop filter top cap shown in FIG. 1;

FIG. 3 is a front view of the drop filter top cap shown in FIG. 1;

FIG. 4 is a back view of the drop filter top cap shown in FIG. 1;

FIG. 5 is a right side view of the drop filter top cap shown in FIG. 1;

FIG. 6 is a left side view of the drop filter top cap shown in FIG. 1; and

FIG. 7 is a top view of the drop filter top cap shown in FIG. 1; and,

FIG. 8 is a bottom view of the drop filter top cap shown in FIG. 1.

The broken lines in the Figures are for contextual purposes and form no part of the claimed design.

1 Claim, 6 Drawing Sheets
